MATTHIAS PLUM, OF NEWARK, NEW JERSEY.

SHEET-SEPARATING MECHANISM.

1,117,592.

Specification of Letters Patent. Patented Nov. 17, 1914.

Application filed August 20, 1908. Serial No. 449,421.

To all whom it may concern:

Be it known that I, LEWIS E. MORRISON, a citizen of the United States of America, and a resident of Newark, Essex county, New Jersey, have invented certain new and useful Improvements in Sheet-Separating Mechanisms, of which the following is a specification.

This invention relates to sheet separating devices and has particular reference to a sheet separating mechanism in which a sheet is separated from a pile of sheets by suction and then conveyed to a secondary feeding or other mechanism of the machine of which the separator forms a part. In the present instance the separating mechanism is designed and illustrated in connection with a printing machine and one object of the invention is to so construct the separating mechanism that it may be readily attached to and detached from an ordinary job press, though it will be apparent that my invention may be used on other types or classes of machines.

Other objects will appear as this specification proceeds while reference is had to the accompanying drawings in which—

Figure 1 is a side elevation of a portion of a job press equipped with my sheet separating mechanism, Fig. 2 is an end view of parts of the operating mechanism shown in Fig. 1, Fig. 3 is a perspective view of the separating and feeding mechanisms, Figs. 4, 5, 6 and 7 are detail views of the separating or suction nozzle.

The reference numeral 1 denotes the frame of the press, 2 is the oscillating form member pivoted at the foot of the press in the usual manner while 4 is the oscillating platen, the operating means for which are not shown as they form no part of this invention. The form member is operated by means of connecting rods 5, only one of which is shown pivoted at 6 to the gear 7 which is driven from the pinion 8 in drive shaft 9.

On the frame of the press are mounted two brackets 10 which support the arms 11 journaled on shaft 12 and supporting at their free ends another shaft 13. Tapes 14 run over these two shafts. Side guides as 15 are adjustably carried by the arms 11, which are also provided with cams 16 resting on rollers 17 mounted on levers 18 pivoted at 19 in the brackets 10. These levers

18, one on each side, in turn rest on rollers 20 carried by the platen. By these means the feeding mechanism follows the movement of the platen and co-operates therewith. The tapes 14 are driven constantly in 60 the direction toward the platen by any suitable means. This feeding mechanism has been described in an application filed by me on the 17th day of February, 1908, Ser. No. 416,203, and it is not necessary that I should 65 here describe it more in detail, it being sufficient for the purpose of understanding this invention to state, that when the feeding mechanism is elevated as in Fig. 1 the sheet is being dropped on the tapes, and when the 70 platen is in the position shown in Fig. 3 the sheet is fed onto the platen by the said tapes. Any suitable stopping means may be used to retain the sheet on the tapes until the platen is in the proper position to receive it. Such 75 stopping means being described in the afore- 80 said application. It should also be noted, that for the purpose of making ready or otherwise getting at the platen or the interior parts of the press, the feeding mechanism may be swung upward around the shaft 12. This feature is here mentioned as it has some influence upon the construction 85 of the suction mechanism as will be seen presently.

In order to separate the top sheet from the pile of sheets I employ a suction nozzle 21. This nozzle is comprised of the short pipe 22 to which is soldered or otherwise fastened an elbow 23. The ends of the nozzle are 90 closed and provided with studs or pins 24. The one side 25 of the nozzle is flattened to better rest on the paper and is provided with perforations 26. See Figs. 5 and 7. The nozzle is pivoted by the pins 24 in the 95 two arms 27 which are fast on the short sleeve 28. This latter is removably mounted on the rod 29 and fastened thereon by the set screw 30. A lug 31 is carried by the nozzle, and an elastic member 32 passes 100 around this member and the set screw 30 and normally keeps the nozzle in the position shown in Fig. 6 with relation to the sleeve 28.

The rod 29 is rigidly mounted in a 105 weighted arm 33 pivoted at 34 on the upright lever 35, which latter is pivoted at 36 on bracket 10. On the arm 33 is pivoted at 37 a bell crank 38 the one arm of which bears against a stop 39 while the other arm 110

is connected at 40 to a connecting link 41, the lower end of which is pivoted at 42 to the cam lever 43 which is pivoted at 44 to the lower end of the aforesaid lever 35. The 5 cam lever is provided with a cam 45.

On the brackets 10 is mounted a feed table 46 having side guides 47 and rear stops 48 for determining the position of the pile of sheets 49. The arm 33 carries a pipe elbow 50 which is connected to the aforesaid nozzle elbow 23 by a hose 51 and to the pump 52 by a hose 53, parts of which have been removed in Fig. 1 for the sake of clearness. The pump is conveniently hinged to a rod 15 64 in the press, and the piston rod is pivoted at 65 to the levers 55.

The lever 35 is oscillated on its pivot 36 in order to swing the nozzle from the position shown in Fig. 3 when it picks up a sheet 20 to the position shown in full lines in Fig. 1 when the sheet is dropped on the tapes 14. The operating means for the lever 35 is as follows. Pivoted at the foot of the press are levers 55 only one of which is shown 25 and the function of which is to operate the gripper carriage 56 on the levers 18 as described in an application filed by me on the 6 day of March, 1908, Ser. No. 419,480. The one lever 55 has an arm 56^a to the end 30 of which is pivoted at 57 a link 58 the other end of which is pivoted at 59 to the connecting rod 5, so that, as the latter reciprocates the levers 55 oscillate on their pivot. A rod 60 joins the lower ends of the levers 35 35 and the said rod abuts the levers 55 as shown in full lines in Fig. 1 and between the said two sets of levers 35 and 55 is the spring 61 shown dotted in Fig. 1 which also shows in full and dotted lines the extreme 40 positions of the various parts.

The one end of the spring 61 is hooked directly to the rod 60 while the other end is hooked to a rod 61^a which latter rod is carried in the arms 61^b secured to the levers 45 55, so that when these latter move to the right in Fig. 1 the spring compels the lower end of the lever 35 to follow until the upper end abuts an adjustable stop 62. Further movement of the levers 55 simply expands the spring 61 as will be clear from the position shown in dotted lines. On the leftward movement of the levers 55 the spring 61 is first contracted until the lever 55 abuts the rod 60. Then the latter is also 55 moved leftward thereby moving the upper part of the lever 35 to the right.

The arm 56^a of the lever 55 carries a stud 63 which coöperates with the cam 45, and this latter and the link 41 and bell crank 38 50 are much lighter than the weighted arm 33 which carries the nozzle, so that normally the cam 45 is forced downwardly and its arm 43 upwardly by the weight of the arm 33 and the nozzle.

The operation is as follows: Fig. 1 shows

the impression being on and the nozzle 21 has just deposited a sheet on the tapes 14. Next the press opens, the form member moves to the right carrying the lever 55 with it into the dotted position, and the lever 55 through the spring 61 oscillates the lever 35 moving this latter until the same abuts the stop 62 when further movement of the lever 55 is taken up by the spring. Thus the nozzle is moved to the left, and just as the lever 55 commences its movement to the right the stud 63 lifts the cam 45 thereby slightly elevating the nozzle and permits the latter to pass freely to the left. The parts are so timed, however, that as the lever 35 abuts the stop 62 the cam 45 is clear of the stud 63 and the nozzle by gravity falls on the edge of the pile of sheets as seen in Fig. 3 and in Fig. 7, and it should be noted in this latter figure, that by reason of the fall of the nozzle on the paper by gravity, the nozzle assumes the position shown in this figure, that is, the flattened surface 25 comes in direct contact with the surface of the paper and the lug 31 is forced away from the sleeve 28. When the impression again takes place the lever 55 moves to the left in Fig. 1, the suction causes the top sheet to adhere to the nozzle and by the stud 63 encountering the cam 45 the nozzle is lifted, and the spring 32 pulls the lug 31 against the sleeve 28. This causes the edge of the top sheet to be turned upwardly as seen in Fig. 6 thus completely separating the top sheet from the pile, and this separation is further augmented by a slight leftward movement of the top sheet caused by the raising of the nozzle through an arc the center of which is the pivot 34. In actual operation this forward or leftward movement of the top sheet with relation to the pile is from $\frac{1}{16}$ to $\frac{3}{16}$ of an inch and I have found that this nozzle will separate perfectly. For different weights of paper I use different size nozzles so as to get a varied suction surface. In 105 changing nozzles it is only necessary to loosen the set screw 30 and disconnect the elbow 23 from the hose 51. As the lever 55 continues its leftward movement the stud 63 keeps the nozzle elevated and the latter is moved to the right to the feeding mechanism. When the lever 55 reaches its extreme leftward position the stud 63 passes under the low part of the cam 45 and the nozzle is lowered, the rod 29 carrying the nozzle coming to rest on the one side guide 15 as seen in Fig. 1. The operation is then repeated. During these operations the bell crank 38 and the weighted arm 33 act as if they were one piece, the bell crank bearing against the stop 39 by the action of the cam 45. If, however, it is desired to get at the press and swing the feeding mechanism upward, the nozzle is first moved out of the way by 115 swinging the arm 33 around its pivot 34.

into the dotted position shown in Fig. 4, hence the reason for pivoting the bell crank 38 on the arm 33. The position of the pivot 34 bears a fixed relation to the angle at which the feed table is inclined if the best results are to be obtained.

In Fig. 4 it will be noted that a line marked *a* is drawn through the center of the pivot 34 and the top rear edge of the feed table 46 and the angle between this line and the top surface of the feed table is marked *b*. I have found, that in order to operate the nozzle so as to separate without the same ever picking up two sheets, this angle must not be less than 5°. By making this angle 5° or more, the action of the nozzle will be perfect irrespective of the height of the pile of paper within reasonable limits.

Various modifications of the particular mechanisms shown may of course take place without departing from the spirit of the invention and the claims. And the term sheets in the latter should be construed to cover units of the material to be separated, as it may happen, that two or more sheets may be fastened together and the units formed into a pile later to be separated, in which case this separating mechanism would be equally useful.

30 I claim:

1. The combination of a suction nozzle, a lever for oscillating the same, a cam mounted on said lever, a movable member adapted to engage said cam at the end of the movements of the said lever in both directions and means actuated by said cam for lifting the said nozzle.

2. A suction nozzle comprising a sleeve, arms depending from the same at the ends thereof, a nozzle member pivoted in the extreme ends of the said arms and comprising a hollow member having a flattened perforated surface contained between the said arms, a lug projecting upward from the said member and adapted to contact with the one side of the said sleeve, a spring between the latter and the lug and a hose connection integral with the said nozzle member and communicating with the latter, the said connection extending beyond the said sleeve in a direction with relation to the same opposite to that of the said lug.

3. The combination of a lever pivoted intermediate its ends, a weighted lever pivoted in the upper end of the said first lever, a suction nozzle secured to the said weighted lever, a cam pivoted in the lower end of the said first lever, operating connections between the said cam and the said weighted lever and mechanism coöperating with the cam for causing the latter to actuate the said operating connections for lifting the said nozzle.

4. The combination of a lever pivoted intermediate its ends, a weighted lever pivoted

in the one end of the said first lever, a suction mechanism secured to the said weighted lever, a cam pivoted in the opposite end of the said first lever, operating connections between the said cam and the said weighted lever and means coöperating with the said cam for causing the latter to actuate the said operating connections for lifting the said mechanism and means for oscillating the said means.

5. The combination of a sheet separating device, movable supporting means for the same and comprising a plurality of interconnected pivoted members, a cam carried on one of said members and mechanism for oscillating said cam and also for operating the cam on its supporting member at the beginning of its oscillations in either direction to actuate another of the said members in the said supporting means.

6. The combination of a separating device, a cam, a lever for supporting said separating device and for normally maintaining said cam in a given position, interconnected levers interposed between the said cam and the said lever and means for operating the said cam to lift the lever through the instrumentality of the said interconnected levers.

7. The combination of an oscillating lever, a weighted lever pivoted intermediate its ends in the upper end of the said oscillating lever, a separating device supported on the said weighted lever, a cam pivoted in the lower end of the said first lever, a stop on the said weighted lever, a dog pivoted on the said lever and adapted to engage the said stop, operating connections between the cam and the said dog and means acting on the said cam to cause the latter to actuate the said dog to lift the said weighted lever against the weight thereof while the said oscillating lever is in motion.

8. The combination of a lever, a rod secured to the same, a suction nozzle adjustably mounted on the said rod, a movable supporting member for the said lever, another movable member and coöperating mechanism interposed between the said members and between one of the latter and the said lever for operating the said nozzle.

9. The combination of a movable form member, a lever oscillated thereby, a stud on the said lever, a second lever, a separating device supported at the top of the latter, a cam secured at the bottom of the said second lever and means for oscillating the said second lever by the said first lever so as to cause the said stud to engage the said cam for operating the said separating device.

10. The combination of a lever pivoted intermediate its ends, supporting means for the same, a separating device supported by the longest arm of the said lever, a pivoted

- cam member, connections between the latter and the other short arm of the aforesaid lever, said cam and connections being of less weight than the said long arm of the lever 5 and the separating device and means for operating said cam to overcome the weight of the said long arm and the device supported thereby for the purpose of lifting the said device. 10 11. The combination of a form member, a lever oscillated thereby, a second lever pivoted intermediate its ends, means for operating said second lever by the said first lever, means for limiting the motion of the 15 second lever before the said first lever has ceased to move, a suction mechanism carried by said second lever, a pump for said suction mechanism and means for operating the said pump from the said first lever. 20 12. The combination of a form member, a lever oscillated thereby, a second lever pivoted intermediate its ends, means for operating said second lever by the said first lever, means for limiting the motion of the 25 second lever before the said first lever has ceased to move, a spring interposed between the said two levers, a suction mechanism carried by said second lever, a pump for said suction mechanism and means for operating the 30 said pump from the said first levers. 13. The combination of a lever pivoted intermediate its ends, a cam pivoted at the lower end of said lever, a suction mechanism pivoted at the upper end of said lever, connections between said mechanism and said cam for moving the latter into a given position, and means for operating said cam to move the said suction mechanism. 35 40 14. The combination of a lever pivoted intermediate its ends, a cam pivoted at the lower end of said lever, a suction mechanism pivoted at the upper end of said lever, connections between said mechanism and said cam for moving the latter into a given position, and means for operating said cam at the beginning of its movements in both directions to move the said suction mechanism. 45 15. The combination of a movable form member, a lever pivoted intermediate its ends, an arm pivoted in the upper end of the said first lever, a suction mechanism carried by said arm, a cam pivoted to the lower end of said first lever, connections between the said cam and the said suction mechanism, said connections being of less weight than the said arm, a member for operating said cam to actuate the said suction mechanism and means for operating the said member from the said form member. 50 55 60 16. The combination of a movable form member, a lever pivoted intermediate its ends, an arm pivoted in the upper end of said first lever, a suction mechanism carried by said arm, a cam pivoted to the lower end of said first lever, connections between the said cam and the said suction mechanism, said connections being of less weight than the said arm, a member for operating said cam to actuate the said suction mechanism and means for operating the said member from the said form member, the said means also serving to oscillate the said first lever. 65 70 Signed at Newark, N. J., this 12th day of Aug., 1908.
